SMOKER'S PIPE

Theophilus E. Neal, Prairie View, Tex.

Application May 29, 1939, Serial No. 276,485

1 Claim. (Cl. 131—205)

This invention relates to an improved smoker's pipe.

The acrid taste of a wet pipe needs no elaboration, as all pipe smokers are only too well aware of enforced periodic efforts with swabs to clean up and dry out a favorite pipe. Saliva as well as condensation from the tobacco in the bowl both contribute, as is recognized. Thus, the latent hunt persists among pipe smokers for a dry pipe, a cool smoke, and some expedient whereby, to draw on the pipe will not, sooner or later, result in stoppage or what is more distasteful, the usual gurgle as the pipe burns low. Admittedly, various attempts have been made heretofore to solve the problem and many variations in the pipe structure itself have been evolved. It is believed inherent experience, however, that detail structural parts in the bowl, stem or other components of a pipe become gummed, clogged and filled with nicotine deposits which natural process soon renders the whole more or less inoperative for the purpose envisaged. In contrast, it is conceived, in the present instance, that the answer lies in structural simplicity; to accept the usual pipe structure and to provide accessories which may be readily installed and which will take advantage of natural laws of physics as regards velocities, expansion, etc., of gases, to provide a means whereby the owner of an average simple pipe of bowl and stem may convert his prized possession into a device of greater efficiency and increased comfort.

An object of the present invention therefore, is to provide accessories for, say an average pipe, which may be readily installed, which will provide a dry, cool smoke, which will make it possible to smoke all of the tobacco in the pipe bowl without caking at the bottom; and wherein, as long as the pipe stem is held in the mouth to exclude the entrance of air to the stem, the structure will tend to conduct a continued burning of the tobacco in the bowl, thus to eliminate the necessity of frequent lighting.

A further object of the invention is to provide a grate near the bottom of the bowl; which grate will be so shaped that it cannot fit the usual bowl unless inclined in the bowl; wherein the inclination of the grate will serve, through gravity, to lead any moisture from the grate to the lower portion thereof to drain ultimately into the bottom of the pipe bowl; and wherein the grate will define an expansion chamber at the bottom of the bowl.

Still another object of the invention is to pro-

vide, in conjunction with the grate, a throat tube leading from the expansion chamber mentioned into the pipe stem; wherein the throat tube will function in the manner of a Venturi tube to increase velocity and reduce pressure; wherein a baffle will be provided at the large end of said tube for changing the direction of flow of gases or smoke from the tobacco chamber to then flow through said tube; and wherein the stem duct will provide, in comparison with the size of the small end of the throat tube, a final expansion chamber for the smoke.

And the invention seeks, as a still further object, to provide accessories which will be simple in construction and which may be readily manufactured and sold at moderate price.

Other and incidental objects of the invention will appear during the course of the following description and in the drawing:

Figure 1 is a side elevation of a pipe, parts being broken away and shown in section to better illustrate the installation of the present improvements.

Figure 2 is an enlarged fragmentary section more particularly showing the construction and mounting of the grate and throat tube of the invention.

Figure 3 is a detail perspective view of the accessories of the invention.

Figure 4 is a fragmentary detail section on the line 4—4 of Figure 2.

Referring now more particularly to the drawing, I have shown a pipe embodying a bowl 10, stem 11 and mouthpiece 12. The usual duct leading from the bottom of the bowl to the mouthpiece is indicated at 13 and, as shall presently appear, the forward end portion of this duct is utilized as an expansion chamber 14. The bowl 10 is internally contracted toward the bottom thereof in the usual manner and thus, near its lower end, is more or less ovate in cross section.

Removably fitting within the bowl is a more or less ovate tilted grate 15 consisting of a flat piece of metal or other suitable material and having a plurality of spaced, inclined openings 16 therethrough of approved shape, number and spacing, the axes of said openings being preferably disposed at an angle to the flat faces of the grate and tilted to the vertical in conformity with the inclination of the grate. At the periphery of the grate is provided a notch 17 through which a short piece of wire or other convenient instrument may be engaged for removing the grate from the bowl. The grate is shaped

at its periphery to fit the ovate cross sectional contour of the lower portion of the bowl when the plate is tilted, as seen in Figures 1 and 2 of the drawing and thus, as will be perceived, the grate cannot be rigidly positioned within the lower portion of the bowl except in a tilted or inclined position. Any attempt to install the grate level will, of course, result in the binding of the grate at more or less diametric points on its periphery against the wall of the bowl so that the grate will teeter while, when the grate comes to rest frictionally fitting throughout its periphery against the wall of the bowl, it will be found that the grate is inclined as shown. Above the grate is provided a tobacco chamber 18 while below the grate is defined an expansion chamber 19.

In conjunction with the grate 15 I provide a longitudinally tapered throat tube 20 which may be of metal or other approved material and is crooked or curved arcuately toward its larger end. Removably fixed over the larger end of the tube is an imperforate closure cap 21 considerably larger in diameter than the adjacent end of the tube and provided with a flaring, annular deflecting flange 22 depending about the tube in spaced relation thereto. Formed in the tube preferably within the zone of said flange are one or more spaced inlet openings 23.

As brought out in Figure 2 of the drawing, the smaller end of the tube 20 frictionally fits in the mouth of the duct 13 and the tube is so arranged that the curved larger end thereof extends upwardly within the expansion chamber 19 of the pipe bowl axially thereof so that the cap 21 lies in contiguous spaced relation parallel to the grate 15. Thus, as will now be realized, both the grate 15 and the throat tube 20 may be readily installed in what may be more or less loosely termed any average conventional pipe.

It will now be assumed that the chamber 18 of the bowl 10 is filled with tobacco to which a flame has been applied and the pipe is in use. Moisture from the tobacco will tend to condense on the grate 15, due, of course, to the comparative coolness thereof and, therefore, since the grate is inclined, necessarily, as previously pointed out, such moisture as well as any other deposits will be caused to flow, by gravity, along the upper surface of the grate to encounter the inclined openings 16 and pass therethrough. As will be seen, the inclination of said openings will render the mouth of each a trap tilted with respect to the path of gravitational flow of the moisture and any moisture not encountering one or more of said openings will creep to the lower margin of the grate and so drain off through the notch 17 into the chamber 19. The condensation on the upper surface of the grate will thus be effectually diverted into the chamber 19. In contrast, were the grate level, the moisture would, as will be appreciated, collect in tiny islands and globules on the upper surface of the grate to clog the openings 16 perhaps and dampen the tobacco as well as possibly cause gurgling as suction was applied to the mouthpiece 12. When desired, the chamber

19 may be readily emptied, simply by removing the grate 15 and inverting the bowl 10. In most instances, however, it will be found unnecessary to remove the grate, as, when the bowl is inverted, moisture in the bowl will drain out through the notch 17 in the grate. If found expedient, the throat tube 20 may also be readily removed and after displacing the cap 21, said tube may be conveniently cleaned.

Upon entering the chamber 19, smoke from the burning tobacco in the chamber 18 will, of course, be drawn toward the throat tube 20 and as the main zone of suction will lie close about the large end of said tube, the smoke will be drawn downwardly or, at least, the major portion thereof, to encounter the cap 21 and deflecting flange 22. Before entering the openings 23 in said tube, the smoke will accordingly be caused, by said cap and flange, to change its direction of flow and allowed to expand in the chamber 19 for dropping moisture. Subsequently, as the smoke enters the throat tube 20 and progresses therethrough, velocity will be increased and pressure reduced, as will be well understood. Thus, as the smoke enters the chamber 14 of the stem 11, which chamber is larger than the small end of the throat tube, expansion will again take place to further cool and dry the smoke. Furthermore, as will be seen, as long as the mouthpiece 12 is held in the mouth to exclude air, the pressure in the chamber 14 will tend to be less than the pressure in the larger chamber 19 with a resultant tendency to keep the tobacco in the pipe burning.

Having thus described my invention, I claim:

A smoker's pipe including a cylindrical bowl internally contracted toward its lower end, a stem extending from the lower end of the bowl and provided with a smoke duct entering the bottom of the bowl, a flat freely removable reticulate grate ovate in peripheral outline to frictionally fit throughout its periphery in contact with the wall of the bowl only in inclined position within the lower portion of the bowl to define a tobacco chamber above the grate and an expansion chamber below the grate communicating with said duct, said grate being inclined to drain moisture from the upper surface thereof and being provided at the lowermost point in its periphery with a notch providing a drain opening through which moisture may escape into said expansion chamber and adapted to receive a wire or the like to engage beneath the grate and lift it out of the bowl, a throat tube uniformly tapered from end to end and frictionally engaged at its smaller end portion in the mouth of said duct, the larger end portion of said tube being curved upwardly within said expansion chamber toward the grate and provided near its adjacent end edge with an inlet, and a closure cap removably fitting over the larger end of said tube to lie substantially parallel to said grate close therebeneath and provided with a flared deflecting flange surrounding the tube at the zone of said opening, the tube with the cap thereon being freely removable through the bowl when the grate is displaced therefrom.
